J. Edward Sheppard

UNITED STATES PATENT OFFICE

THOMAS CAHILL, OF ARDMORE, PENNSYLVANIA, ASSIGNOR TO JOSEPH SAUER, OF PHILADELPHIA, PENNSYLVANIA

SCOURING DEVICE

Application filed March 12, 1929. Serial No. 346,432.

This invention relates to scouring devices, particularly to that kind thereof wherein steel or other metal wool is the scouring element.

5 One of the objects of this invention is to provide a cheap and serviceable holder for metal wool, which will shield the hand of the user both when attaching the scouring pad and when using the same.

10 A further object is to provide a scouring pad holder made up of wood and a piece of spring steel wire, bent in such a form, that the point of the hook end of the wire, will be directed downwardly at an angle, for readily 15 forcing the said point into the pad, without touching the pad with either hand, and when pushed up against the holder by forcing the handle down, to have the hook turn to compress the pad up against the handle, and at 20 the same time lock the wire in this up-position.

With these and other objects, my invention resides in certain construction, one embodiment of which is illustrated in the drawings, 25 wherein like figures of reference refer to like parts, is hereinafter described, its operation is explained and what I claim is set forth.

In the drawings,

30 Figure 1 is a side elevation of a scouring device embodying my invention, and is shown partly broken away to illustrate the internal construction.

Figure 2 is a bottom plan of the device shown in Figure 1, illustrating a fragment 35 of circular steel wool pad attached to the holder.

Figure 3 is a top plan of the device shown in Figure 1.

40 Figure 4 is a sectional elevation of the device, through Figure 5, showing the hook extended in position to enter the steel wool pad.

Figure 5 is a bottom plan of the holder shown in Figure 4.

45 Figure 6 is a top plan of the holder shown in Figure 4.

In the figures, the circular handle 10, preferably made of wood, is shown to have a central long bore 11, opening below into a shallow circular pocket 12, concentric thereto and greater in diameter than the bore 11. The bore 11 opens above into a cylindrical pocket 13, concentric with, but of greater diameter than the bore 11. This pocket 13 opens above into a larger pocket 14 concentric thereto, and in the top of the holder. A conical shoulder 15 is formed between the bore 11 and the pocket 13, while a conical shoulder 16 is formed between the pockets 13 and 14. The handle 10 has a spherical body 17, terminating in a neck 18, below which is a flared shoe portion 19, in which is the shallow pocket 12. About the neck 18, is the flexible shield 20, which may be of sheet rubber, cloth or any other suitable material.

50 A wire member 21, is formed to function with the bore 11, the shoulders 15 and 16 and the pocket 12. This member 21 is made of a single piece of spring wire, with a loop 22 at the top, and is bent to form a heel 23. The loop 22 is firmly fixed in the slot 24, of the cap 25, and is further secured by a cross pin 26. The wire 21 has two long portions 27 and 28, 55 integral with a central loop 29. The upper part of the portion 27 terminates in the loop 22, while the lower part of the portion 28 terminates in a straight long pointed hook 30, bent at right angles with the portion 28. The side elevation of this wire member 21, is 60 shown in Figure 4 to be near its normal unstrained shape, with the portions 27 and 28 at an appreciable angle to one another, with the point 31, of the hook 30, downward. While 65 in Figure 1, the wire member 21 is shown in a strained or forced bent position with the portions 27 and 28 nearly parallel. The circular 70 scouring pad is marked 33.

75 When assembling the member 21, with the handle 10, having the cap 25, of a diameter adapted to slide into the bore 11, the cap 25 is moved up into the bore 11, until the heel 22 80

engages the conical shoulder 15. At the same time, the portion 28 bears against the inner circular edge 34, of the pocket 12, and the loop 29 bears, in the opposite direction, against the 5 wall of the bore 11, causing a forced bending of the member 21, that decreases the otherwise normal, unstrained, angle between the portions 27 and 28.

With the pad 33 resting on a firm surface 35, (see Figure 4) and the point 31, of the hook 30 placed a little back of the center of the pad 33, the handle 10 is firmly gripped by one hand of the operator and pressed down, while the fingers touch the top side 10 of the shield 20. The hook 30 is thus imbedded into the meshes of the pad 33, and as the point 31, of the hook 30, bears against the hard surface 35, the member 21 is shoved up into the bore 11 and the pockets 13 and 15. The heel 22, at the same time, travels up and snaps over the upper shoulder 16, due to flexed action occurring in the length 20 of the member 21, as the portion 28, moves up as it bears against the edge 34, straightening 25 out the member 21, putting the same in a strained spring condition, whereby the strain comes in connection with a bearing point at the wall of the pocket 14 and a bearing point at the edge 34, both these bearing points 30 being on one side of the member 21, and an intermediate bearing point of the central loop 29, against the wall of the bore 11 on the opposite side of the member 21, as shown in Figure 1. The hook 30 then becomes horizontal, drawing the central portion of the 35 pad 33 up into the pocket 12, compressing the steel wool of the pad up against the inverted bottom of the pocket 12, as shown in Figure 1.

40 To release the pad, the cap 25, in the pocket 14, is pressed radially inward to dislodge the heel 23 from hooked engagement with the conical shoulder 16, and then is pressed downward into the pocket 13, until the heel 45 23 engages the shoulder 15, and the hook 30 points downward at the angle shown in Figure 4, when the pad 33 can be easily released.

With the heel 22 engaging the shoulder 15, 50 the member 21 is prevented from falling out of the handle 10. While the member 21 is of a single piece of wire and is easily formed, the functioning of its parts, in tending to resume their normal positions with respect to one another, when sprung from their angular relation, during a longitudinal movement within the handle 10, effects the desired releasable attachment of the pad 33 with the 55 handle 10 in a quick and practical manner without touching the hand to the pad 33. The flexible shield affords protecting means to the fingers either when operating on an extended surface or the surface of a thin 60 cylindrical object like the handle of a tea 65

pot or metal cup, in which event the pad is bent around the object being cleaned.

While I have illustrated and described but one embodiment of my invention, changes therein can be made without departing from the spirit and scope thereof, I therefore wish to include all forms which come within the purview of the appended claims.

I claim,

1. A scouring device comprising a pad, a handle having a hole axially positioned therethrough, a shoulder on the wall forming said hole, a bent wire member laterally sprung within said hole, a heel portion at one end of said member and a hook portion at the opposite end thereof extending beyond the lower end of said hole, with the point of said hook below the transverse plane of said lower end of said hole, projecting outward with respect to said hole, said heel portion being adapted for releasable engagement with said shoulder.

2. A scouring device comprising a pad, a handle having an axial hole therethrough, a spring wire member adapted for manual reciprocation within said axial hole, a shoulder on the wall forming said hole, said member comprising a heel portion at its upper end adapted to engage said shoulder, a hook portion at its lower end extending below said hole and away therefrom and a loop portion intermediate of the ends of said member, said member being sprung within and across said hole to have said loop in sliding spring pressed engagement with the wall of said hole, whereby said heel is adapted to snap onto said shoulder, and said hook is given an angular movement when attaching said pad to said handle.

3. A scouring device comprising a pad, a handle having an axial hole therethrough, a shoe portion at one end of said handle, a shallow pocket in said shoe portion co-axial with said hole, two shoulders longitudinally spaced on the wall of said hole, a wire member having a heel portion at its upper end, and a hook portion at its lower end for engaging said pad, said wire member being bent and sprung within and across said hole whereby said heel portion can be snapped into engagement with either of said shoulders during a longitudinal movement of said wire member.

4. A scouring device comprising a pad, a handle provided with an axial hole therethrough, having three portions of differing diameters, the intermediate portion being larger than the lower portion and smaller than the upper portion whereby an annular shoulder is formed at each end of said intermediate portion, a bent wire member within said hole and sprung across the hole, a heel portion at the upper end of said member adapted for engagement with either of said shoulders and a hook portion at the lower

end of said member protruding below said handle and adapted for engagement with said pad.

5. A scouring device having a handle with an axial hole therethrough, having three portions each of a greater diameter than the portion below it, thus forming two annular ledges within said hole, a wire member and a cap on one end, a hook on the other end of said wire member, and a heel portion on said wire member below said cap, said wire member being sprung across said hole and adapted to have said heel snap into engagement with either of said ledges during an upward longitudinal movement of said wire member within said hole.

THOMAS CAHILL.
